[57] CLAIM

The ornamental design for a compartmented keyboard drawer, as shown and described.

DESCRIPTION

FIG. 1 is a perspective view of a compartmented keyboard drawer showing our new design, the broken line drawing of a computer stand is for illustrative purposes only and forms no part of the claimed design;

FIG. 2 is a perspective view thereof, the side shelf shown in an "out" position;

FIG. 3 is a perspective view thereof, the utility compartment shown in an "open" position;

FIG. 4 is a top plan view thereof;

FIG. 5 is a front elevational view thereof;

FIG. 6 is a left side elevational view thereof, the right side being a mirror image; and,

FIG. 7 is a rear elevational view thereof.
